UNITED STATES PATENT OFFICE.

SAMUEL S. STEVENS, OF HOOSICK, NEW YORK.

PULP-ENGINE.

SPECIFICATION forming part of Letters Patent No. 634,038, dated October 3, 1899.

Application filed February 9, 1898. Serial No. 669,629. (No model.)

To all whom it may concern:

Be it known that I, SAMUEL S. STEVENS, a citizen of the United States, residing at North Hoosick, county of Rensselaer, and State of New York, have invented certain new and useful Improvements in Pulp-Engines, of which the following is a specification.

The invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures.

Figure 1 of the drawings is a top plan view of my improved pulp-engine. Fig. 2 is a side elevation of the same with portions of the side wall and main plate broken away. Fig. 3 is a vertical cross-section taken on the broken line 3 3 in Fig. 1.

A is the vat, provided with the usual well-known rounded ends A' and A², plate A³, beater-roll A⁴, bed-plate A⁵, and back fall A⁶. The plate divides the interior of the vat into two side channels, the return-channel A⁷ and the roll-channel A⁸, in the usual manner.

The object of my invention is to divide the current produced by a single roll and deliver the divisive or resulting currents separately into stratifying-channels interposed between the roll and the return channel, whereby the divisive currents are superposed one upon the other and returned to the roll in horizontally-disposed layers or strata superposed one upon the other.

My invention consists of a divisive plate extending from near the roll backward whereby the current from a single roll is divided into two parallel currents, which are delivered, respectively, to the separate channels of the stratifying apparatus.

B is the divisive plate, the forward end of which presents a sharp vertical edge in close proximity to the roll. The back end is provided with an upright B², having a screw-threaded aperture adapted to receive the supporting and adjusting screw B³, rotary in the

bearings B⁴ and held from sliding lengthwise in such bearings by the shoulders B⁵ and B⁶ on the screw-stem.

The divisive plate is preferably made of bronze metal, with its forward end resting in a slot in the back fall.

A platform A⁹ is erected in the vat-channel just back of the back fall, which extends from the back fall and the divisive plate around the curved end A² of the vat to the return-channel A⁷, forming an overlying channel B⁸, extending from the roll around the curved end A² to the discharge-opening at A¹⁰. On the opposite side of the divisive plate is formed a conduit-channel B⁹, extending from the roll around the curved end A² of the vat beneath the platform A⁹ to the discharge-opening A¹².

The discharge-openings are each of the same width as the return-channel A⁷, with one subjacent to the other, so that the stock passes along the return-channel around the curved end A² to the roll in stratified form, the divisive currents forming the respective strata.

That part of the apparatus which receives the divisive currents and disposes them in layers or strata was not conceived by me and I do not broadly claim the same.

I prefer to raise the bottom of the vat at the back end and provide the incline C, so that the flow of the stratified stock will be facilitated down the incline from one end of the vat to the other.

The use of my improved apparatus positively controls the stock, so that one-half the stock, which is engaged by one end of the beater-roll during a given passage of the stock between the roll and bed-plate, is sure to be engaged by the other end of the roll during the next passage of the stock between the roll and bed-plate. This is essential to the rapid production of uniform stock, for the reason that it is difficult or impossible to so adjust the knives of the roll and bed-plate that each end of the roll will do exactly the same quality of work.

By transferring the stock from one end of the roll to the other in a regular and positive manner, as above described, I am able to secure practical uniformity of stock.

The proximity of the divisive plate to the roll can be adjusted as desired by means of the hand-wheel H on the screw-stem B³. What I claim as new, and desire to secure 5 by Letters Patent, is—

In a pulp beating and mixing engine, the combination with a beating-roll; of a divisive plate dividing the back part of the roll-channel and movable toward and from the roll; and means for adjustably moving the divisive

plate; and stratifying-channels leading from the divisive plate to the return-channel, substantially as described.

In testimony whereof I have hereunto set my hand this 15th day of January, 1898.

S. S. STEVENS.
